PULSATOR FOR PULSATORY TOOLS.

1,126,959.

Specification of Letters Patent.

Patented Feb. 2, 1915.

Application filed March 26, 1912. Serial No. 686,432.

To all whom it may concern:

Be it known that I, CLARENCE A. DAWLEY, a citizen of the United States, residing in Plainfield, in the county of Union and State of New Jersey, (whose post-office address is 39 Cortlandt street, New York, N. Y.,) have invented certain new and useful Improvements in Pulsators for Pulsatory Tools, of which the following is a specification.

10 This invention relates to pulsators for pulsatory tools and more particularly to a double cylinder pulsator adapted for use with tools of the free piston or hammer type.

In the double cylinder pulsators heretofore used the cylinders have both developed the same compression, furnishing equal power to both sides of the tool operated thereby, either because when independent, the cylinders were of the same design or 20 when connected the cylinders both opened into the same crank case and drew from the same air supply. In the operation of hammer tools however, very little power is required in the front end of the tool cylinder 25 on account of the rebound of the piston, and hence the pressure in this end of the tool cylinder can advantageously be less than in the back end. This result can only be obtained effectively by having a pulsator with 30 two pressure spaces maintained at different pressures.

The object of the present invention is to provide a pulsator wherein this result is obtained, and to this end, I have devised a 35 pulsator, a practical embodiment of which is shown in the accompanying drawings in which:

Figure 1 is a side elevation partly in section of the complete pulsator. Fig. 2 is a 40 sectional view showing a detail of the piston and crank construction.

The pulsator as shown comprises a high pressure cylinder 1 and a low pressure cylinder 2. In the cylinders are pistons 3 and 4 which are operated by rods 5 and 6. The head of each is pivotally held as shown in cylinder 1 in Fig. 1 and in Fig. 2 by a pin 7 which bridges a recess 8 in the piston. This construction is used in order that the 45 crank end of the piston shall have as little clearance as possible. The other ends of rods 5 and 6 are attached to crank pins 9 and 10, which are mounted on crank disks 11 and 12. These crank disks are rotated by 50 the shaft 13 of a motor 14. In the present

case they are shown as directly connected to the shaft of the motor although of course intermediate gearing may be used.

In order to maintain the two cylinders at different pressures one end of each, in this 60 case the back or free end, is used as a tool operating chamber while the front or crank ends of the cylinders are constructed to operate as pumps, their different clearances giving different pressures. To obtain this 65 result the crank cases 15 and 16 are made air tight, the crank case 15 on the high pressure cylinder forming a clearance chamber 17 smaller than the low pressure cylinder clearance chamber 18. Air is admitted into the 70 clearance spaces through check valves 19 and 20 which open into the clearances at any desired points. In order to convey air from one side of the piston to the other to build up the pressure in the tool operating pressure chambers, ports 21 and 22 are provided 75 which just bridge the pistons at the lowest point of their strokes.

As an additional means of building up pressure in the high pressure cylinder, when 80 a higher pressure is desired than is practicable on account of the necessary size of the clearance space 17, air may be taken into it from the low pressure cylinder, which is at a pressure above atmospheric and the 85 pressure in the high pressure cylinder stepped up to this extent. To do this a pipe 23 is provided, which leads from a valve chest 24 on cylinder 2, from which ports 25 and 26 lead to different points along the cylinder, these ports being controlled by check valves 27 and 28 which can be adjusted or closed by screws 29 and 30. The high pressure cylinder is provided with a valve chest 31 from which ports 32 and 33 lead to the 90 cylinder, the lower port 33 having a screw 34 adapted to close it.

From the upper ends of cylinders which form the pressure chambers for operating the tool fluid conduits 35 and 36 lead to the 100 opposite sides of the piston of the tool to be operated. (Not shown.)

In operation the pulsator may be used in a variety of ways. When it is desired to maintain a large difference in pressure between the cylinders the check valve at port 25 should be seated as lightly as possible and port 33 should be open. On the up stroke of piston 4 air will be drawn in through valve 20 from the atmosphere. On 110

the down stroke of piston 4 the air will be compressed in the crank case 16 and will reach its maximum pressure just before the piston is bridged by the port 22 which allows the pressure to be equalized on both sides of piston 4. At the point of maximum pressure the piston 3 will be nearly at the top of its stroke affording a large space for the compressed air in crank case 16 to flow into. 5
10 At the end of the down stroke of piston 3 the pressures on both sides of piston 3 will equalize, thus allowing air to flow into the tool operating end of cylinder 1. In this way the pressure will be stepped up in the 15 high pressure cylinder, until the pressure in the crank end of the cylinder 1 at substantially the end of its up stroke is equal to the maximum pressure possible in crank case 16 which is limited of course by the size of the 20 clearance in this cylinder, the pressure at the end of the up stroke of piston 4 never being greater than atmospheric pressure.

If it is desired to maintain a smaller difference in pressures between the cylinders, 25 the ports 25 and 26 can be closed by screwing down adjusting screws 29 and 30. In this case the difference in pressure in the two cylinders will be caused by the difference in the size of the clearance spaces in the 30 crank ends of the cylinders. The clearance space in cylinder 1 being smaller than in cylinder 2, a greater pressure can be built up in this cylinder as the check valves 19 and 20 allow the pressure at the end of the 35 up stroke of each piston to reach atmospheric pressure.

All gradations of difference in pressure between the two mentioned above can be obtained by adjusting valves 27 and 28 by 40 means of screws 29 and 30.

If it is to be desired to operate both cylinders of the pulsator at the same pressure, port 33 can be opened and check valve 27 temporarily removed or otherwise arranged, 45 to allow port 25 to be fully opened. Comparatively little pressure will be built up in the system in this way, the tool operating at very little above atmospheric pressure. The check valves 19 and 20 prevent any part of 50 the system from going below atmospheric pressure however.

Although the pipe 23 and valve chests 24 and 31 are shown as a means for increasing the pressure difference between the cylinders, 55 beyond that which can be obtained by differences in the clearance spaces of the cylinder, nevertheless where a smaller range of differences between the pressures in the cylinders is required or where still higher pressure in the whole system is desired, both the cylinders may have the same clearance and the check valves 27 and 28 and pipe 23 alone depended on to produce the difference in pressure between the two cylinders.

60 It is to be understood that the device as

shown and described discloses only one modification of my pulsator and other changed and modified forms are included within the spirit and scope of my invention as expressed in the claims.

70 What I claim is:

1. In a pulsator for pulsatory tools, the combination of two cylinders, pistons in said cylinders, one end of each of said cylinders forming a tool operating pressure chamber 75 and the other end a pressure building pump for one of said pressure chambers, said pressure building pumps having different clearances and supplying fluid at different pressures to said pressure chambers to maintain 80 a difference in pressure between said chambers.

2. In a pulsator for pulsatory tools, the combination of two cylinders, pistons in said cylinders, one end of each cylinder forming 85 a tool operating pressure chamber and the other end a pressure building pump for one of said pressure chambers, said pumps having different clearances, and supplying fluid at different pressures to said pressure chambers, and means for supplying fluid under 90 pressure from the cylinder of lower pressure to the pump of the cylinder of higher pressure.

3. In a pulsator for pulsatory tools, the 95 combination of two cylinders, pistons in said cylinders, one end of each of said cylinders forming a tool operating pressure chamber and the other end a pressure building pump for supplying fluid under pressure to one of 100 said pressure chambers, and means for supplying fluid under pressure from one of said cylinders to the pressure building pump of the other.

4. In a pulsator for pulsatory tools, the 105 combination of two cylinders, pistons in said cylinders, one end of each of said cylinders forming a tool operating pressure chamber, and the other end a pressure building pump for supplying fluid under pressure to the 110 corresponding pressure chamber, and a fluid conduit having check valve mechanism therein leading from one cylinder to the pressure building pump of the other whereby fluid already under pressure is supplied to the 115 pump of the second cylinder.

5. In a pulsator for pulsatory tools, the combination of two cylinders, pistons in said cylinders, one end of each of said cylinders forming a tool operating pressure chamber, 120 and the other end a pressure building pump for supplying fluid under pressure to the corresponding pressure chamber, said pumps having different clearances and adapted to supply fluid to and maintain their respective pressure chambers at different pressures, and a fluid conduit connecting said pumps.

6. In a pulsator for pulsatory tools, the combination of two cylinders, pistons in said cylinders, one end of each of said cylinders 125

forming a tool operating pressure chamber and the other end a pressure building pump for supplying fluid under pressure to the corresponding pressure chamber, a fluid conduit connecting said pumps, said conduit having a plurality of ports leading into one of said pumps, and check valves controlling said ports.

7. In a pulsator for pulsatory tools, the combination of two cylinders, pistons in said cylinders, one end of each of said cylinders forming a tool operating pressure chamber and the other end a pressure building pump for supplying fluid under pressure to the corresponding pressure chamber, said pumps having different clearances and adapted to supply fluid to and maintain their respective pressure chambers at different pressures, a fluid conduit connecting said pumps, said conduit having adjustable check valve mechanism therein to allow fluid to pass from the lower to the higher pressure cylinder.

8. In a pulsator for pulsatory tools, the combination of two cylinders, and pistons in 25 said cylinders, the ends of said cylinders forming two tool operating pressure chambers and two pressure building pumps for said pressure chambers, said pressure building pumps having different clearances and 30 supplying fluid at different pressures to maintain a difference in pressure between said chambers.

9. In a pulsator for pulsatory tools, the combination of two cylinders, pistons in said 35 cylinders, the ends of said cylinders forming two tool operating pressure chambers, and two pressure building pumps for said pressure chambers, and means for supplying fluid under pressure from one of said pressure building pumps to the other.
